UNITED STATES PATENT OFFICE.

FREDERICK HANNAN, OF HUDDERSFIELD, ENGLAND.

LINK CHAIN.

Application filed April 15, 1926, Serial No. 102,354, and in Great Britain April 16, 1925.

This invention comprises certain improvements in link chains and travelling grates for steam boilers or the like.

According to the present improvements, the 5 links are adapted to have a lateral pivotal movement in relation to one another, whilst being prevented from pivoting about a longitudinal axis. The links are also adapted to have a pivotal movement, in relation to one 10 another, about a transverse axis or an angular pivotal movement. The links are, in the hereafter described embodiment, formed in a chain by merely hooking the links together, in such a manner that the links 15 cannot normally become detached or move longitudinally in relation to one another when the chain is in use or in an operative position. The hook and eye elements also form the pivot elements. By this invention 20 also, an improved arrangement of chain is obtained.

Referring to the drawings:

Figure 1 is a plan view of a link constructed according to this invention.

25 Figure 2 is a section on line $\alpha\alpha$ of Figure 1.

Figure 3 is a side elevation.

Figure 4 is an underside view of the link shown by Figures 1 and 2.

30 Figure 5 is a plan view of a modified form of link.

Figure 6 is a section on line $\alpha\alpha$ of Figure 4.

Figure 7 is a sectional plan view of a boiler 35 constructed according to this invention, the left hand flue showing one chain grate in position, whilst the return portion of the other chain only is shown, and the other flue showing the supporting frame.

40 Figure 8 is an elevation showing one flue in section on line $a a$ of Figure 1.

Figure 9 is a side elevation of the side bracket.

According to one form of this invention, 45 each link comprises a head 1 having a convex outer side 2 and a concave inner side 3 of the same curvature; in order that a series of heads can nest together, and in order that the heads may slide laterally in relation to 50 one another. Two arms of a looped member 4 project from the sides of this head on the concave side, such arms first depending slightly below the head, and afterwards lying in a plane parallel to the plane of the 55 head. A tongue or L-shaped member 5,

which is curved at the bend, depends downwardly from the centre of the head at the said concave side. The centre of the vertical limb 5^a of this L-shaped member lies at the centre of curvature of the convex side 2 of the head, whilst the centre of curvature 23 of the said loop 4 lies at the centre of curvature of the concave side 3 of the head. The horizontal or inturned portion 5^b of the L-shaped arm lies below the plane of the said looped member. When therefore the L-shaped member 5 is engaged in the loop 4 of the next adjacent link, it will be seen that the links are flexible in a lateral direction to follow any path, the members 5 and loops 4 forming pivotal members. As the heads of the links abut against one another, longitudinal movement in relation to one another is prevented. The links are of such dimensions that the L-shaped members 5 can only be engaged in the loops when the links are turned inwards at a considerable angle, and therefore any liability of the links becoming accidentally detached is prevented. The concave side of the head may have vertical grooves 24 therein to form air spaces. The L-shaped members can also pivot on the looped members to allow the links to pivot in relation to one another about a transverse axis, when passing around a drum or other 85 curved surface. A curved slot 25 may be formed vertically through the head of the link to form air openings.

Figures 5 and 6 illustrate a modified form of link in which the looped extension 4^a is 90 jointed to the head 1^a by the central stem 4^b.

A chain formed of the links thus described, can readily be adapted for a variety of uses.

Figures 7 to 9 illustrate a chain of links 95 aforesaid applied to the travelling grate of a Lancashire boiler. The chain is mounted on suitable pulleys or guide rollers, and the chain passes longitudinally from the front of the furnace to the rear, then back to the front and then back again to the rear 100 of the furnace, the chain passing over pulleys at the rear and front of the furnace and under the grate to form a continuous chain. Two chain grates are mounted in each flue. Each chain passes round a guide block 6 at the rear of the flue and the guide block 7 at the front of the flue and each chain grate also passes and meshes round a pulley 8 and back under the grate to mesh the pulley 9 at the front of the flue. The 110

return portion of the chain grate is guided from and to the pulleys 8 and 9 by the guide blocks 10. The pulleys 9 are mounted on the driving shaft 11 which is driven by way 5 of the cone pulley 12 and the gear box 13. The recesses 8^a receive the bottom of the members 4. The chain grates pass under the hopper 14 and feed the fuel into the furnace. The ash is received on a dumping 10 plate 15 and is pushed thereup into a suitable receptacle or recess by the ashes leaving the grate. The chain grate is adjusted by mounting the guide blocks 8 in tension blocks 16 which are adjusted by means of 15 the tension screw 17. The links of the chain, being constructed as aforescribed, enables the links to pass round a curved path of small radius and consequently the longitudinal runs of the chain grate are located close 20 together, and the space between each longitudinal run is closed by fire bars 18. These fire bars 18 are detachably mounted in the supports 19 carried by transverse members 20 which are fixed to the longitudinal members 25 or side brackets 21. The supporting framework thus formed is carried at the rear by the frame 22. The guide blocks are also mounted on the transverse members 20. A regulating plate 22 is slidably mounted to 30 adjust the height of opening above the chain and thereby adjust the quantity of fuel carried forward by the chain.

The fire grate is thus formed by two chains which each form three parallel runs 35 or rows of links and each adjacent run of links travel in opposite directions. The green coal thus travels rearwardly on the longitudinal run *a* and is ignited by the burning fuel moving forwardly on the longitudinal run *b*. The surface of the chain 40 grate slopes to the back of the boiler as shown by Figure 9. A forced draught is passed up through the grate.

By this invention therefore a continuous 45 and regular supply of fuel is fed into the furnace. An even heat is also obtained and complete combustion of the fuel.

I claim:-

1. A chain link comprising a head having 50 a convex curved outer side and a concave curved inner side, a looped depending extension and a depending hook-shaped member both formed solid with the head so that the links of a chain of such links 55 can pivot about a vertical axis and retain a continuous surface, and also pivot about a

transverse axis for passing over a pulley or the like.

2. A chain link comprising a head having a convex curved outer side and a concave curved inner side, a looped depending extension and a depending hook-shaped member both formed solid with the head and both located on one side of the head so that the links of a chain of such links can pivot 60 about a vertical axis to retain a continuous surface and also pivot about a transverse axis passing over a pulley or the like.

3. A chain link comprising a head having a convex outer side and a concave inner side, a depending hook shaped member the vertical stem of which lies concentric with the concave outer face, and a depending looped extension to form a pivot member to pivot 70 about an axis concentric with the said inner 75 concave edge.

4. A continuous chain of links in which each link comprises a head having a convex curved outer side and a concave curved inner side, a looped depending extension and a depending hook shaped member both formed solid with the head so that the links of a chain of such links can pivot about a vertical axis to retain a continuous surface and also pivot about a transverse axis, which 80 chain passes substantially horizontally forwardly and backward to form three parallel runs, guide blocks around which the link chain passes, a pulley at one end over which the link chain passes to direct the return portion of the chain, and a pulley at the other end over which the return portion of the chain passes.

5. A continuous chain of links in which each link comprises a head having a convex curved outer side and a concave curved inner side, a looped depending extension and a depending hook shaped member both formed solid with the head, so that the links of a chain of such links can pivot about a vertical axis to retain a continuous surface and also pivot about a transverse axis, which 90 chain passes substantially horizontally forwardly and backwardly to form three parallel runs, guide blocks around which the link chain passes, a stationary bar between each outer and inner run of chains, and a pulley 95 at each end over which the link chain passes.

In witness whereof I have signed this specification.

FREDERICK HANNAN.
